UNITED STATES PATENT OFFICE.

BENJAMIN C. SKINNER, OF BERKELEY, CALIFORNIA, ASSIGNOR, BY MESNE ASSIGNMENTS, TO ELECTRIC RENOVATOR MANUFACTURING COMPANY, A CORPORATION OF PENNSYLVANIA.

PNEUMATIC CARPET-SWEEPER.

1,185,354.

Specification of Letters Patent. Patented May 30, 1916.

Application filed March 13, 1906. Serial No. 305,862.

To all whom it may concern:

Be it known that I, BENJAMIN C. SKINNER, a citizen of the United States, residing at Berkeley, in the county of Alameda and State of California, have invented certain new and useful Improvements in Pneumatic Carpet Sweepers, of which the following is a specification.

This invention relates to improvements in pneumatic renovators, and especially to improvements in that type of apparatus disclosed in an application filed by Alonzo E. Chapman on October 31st, 1905, Serial Number 285,239.

As set forth in the above mentioned application, the leading feature of this type of apparatus is the provision of a light, self-contained, manually propelled machine which may be readily moved from place to place, and over the surface to be cleaned. This lightness and compactness, however, in no way effects the efficiency of the machine, as, by a peculiar arrangement of the motor driven fan, a very powerful suction is produced.

The primary object of the present invention is to provide means for protecting the bearings of the rotary parts from the entrance of lint and similar material in larger particles than the ordinary dust, and which, unless special provision is made, tend to clog up said bearings and impair the operation of the device.

A further object of the invention is to provide improved means whereby the machine may be readily and quickly adapted for cleaning either floors, or walls, furniture, etc.

A further object is to provide an improved arrangement of supporting wheels for the machine, whereby the same may be more conveniently manipulated.

With the above and other objects in view, my invention consists in the construction and arrangement of parts hereinafter described and illustrated in the accompanying drawings, in which:—

Figure 1 is a broken plan view of the renovator equipped with my improvement; Fig. 2 is a broken side elevation of the same; Fig. 3 is a broken detail vertical sectional view on the line 3—3 of Fig. 2; and Fig. 4 is a similar view on the line 4—4 of Fig. 1.

Referring to the drawing in detail, 1 represents a handle, by which the carpet sweeper is moved about on the floor, the upper portion of the handle being broken away. It is attached at its lower end to one end of a platform 2, which carries an electro-motor 3, supplied with electricity by means of the binding posts 4, to which a flexible conductor cord (not shown) is attached. On the other end of the shaft 5 which extends outside the motor, are mounted a pair of fans 6, 7, which rotate in separate casings 8, 9. On the extreme end of the shaft 5 is a pulley 10 around which travels a belt 11 passing also around a pulley 12 upon the shaft of a brush 13, said brush revolving in a casing 14 secured to the frame 15 of the apparatus. This casing is provided at its bottom with a suction mouth, the edges of which, as clearly shown in Fig. 2, make direct, flat contact with the floor or surface to be cleaned, and serve as a support for one end of the platform.

The brush 13, is not essential to the operation of the apparatus, as the cleaning action is due primarily to suction, but, when employed, serves as a beater or stirrer to loosen up the dust and facilitate its removal.

The dust laden air from the brush casing leads by a conduit 15 to the center of the casing 8 and is forced out by centrifugal force to the periphery thereof, whence it passes by a conduit 16 to the center of the casing 9 of the second fan. By means of this second fan it is discharged into the conduit 17 leading to any suitable dust-collector or receptacle (not shown).

All of the above parts may be of the usual or any preferred construction.

The present invention provides means which I will now describe for preventing the entrance of particles of lint or the like into the bearings of the shaft 5. For this purpose the dust laden air from the brush chamber 14 before entering the conduit 15 is caused to pass through a separating chamber 18 across which is extended a wire or other foraminous screen 19 by which the larger particles of lint are arrested. It will be noted that this screen is arranged to overhang a box 20 contained in said separating chamber 18 so that the dust particles caught by the screen will drop into said box. Said

chamber has an opening at one end closed by a flanged door 22 having therein a glass window 23, and made air tight by a rubber packing 24. Through said window the amount of material collected in the box may be observed, and from time to time the chamber may be opened and the box removed and emptied. There is also provided a scraper 25 operated by a rod 26 passing through a small aperture in the door 22 of the chamber, which may be moved over the screen at suitable intervals to scrape the lint or other material therefrom. By the use of the separating chamber and screen, all particles of such size as not to be readily carried out by the current of air, are excluded from passing through the blowers, thereby preventing said particles entering the bearings and causing undue friction.

As clearly shown in Fig. 2, a branch 15^a extends from the conduit 15, and valve means 15^b and 15^c are located in the branch and main conduits respectively. These valve devices are adapted to be operated by means of a handle 15^d.

A flexible hose (not shown) carrying at its end any suitable nozzle, may be attached to the branch conduit, and employed to remove the dust from walls, furniture, etc. By means of the valve devices above described, the fan may be put into communication with either the casing 14, having the suction mouth, or with the branch conduit connected with the hose and nozzle, thus readily adapting the machine to a variety of uses.

The platform 2 is supported along a single line only, on rollers or wheels 2' located intermediate its ends, but preferably adjacent the handle end, at a point between the handle and the axis of the motor. The wheels 2' are of relatively large diameter, in order to elevate the platform above the floor to facilitate the handling of the machine, and the weight of the motor and brush casing cause the platform to normally assume the inclined position shown in Fig. 2. In order, therefore, for the suction mouth to make flat contact with the surface on which the wheels rest, its edges project below the bottom of the platform, and lie in a plane making a sharp angle therewith.

By bearing down on the handle 1, the platform 2 may be tilted above the axis of the wheels or rollers 2', and thus the suction mouth lifted clear of the floor. In this position, the machine may be freely moved from place to place.

What I claim is:—

1. A manually movable pneumatic renovator comprising a platform, suction producing means carried by said platform, a suction mouth also carried by said platform, a conduit connecting said suction mouth and suction producing means, a branch conduit

extending from said main conduit, and means for controlling the passage of air through said conduits.

2. A manually movable pneumatic renovator comprising a platform supported on rollers, a suction mouth and separating chamber carried thereby, suction producing means also carried thereby, a conduit connecting said chamber and said suction producing means, a branch conduit extending from said main conduit, and valve means controlling the passage of air through said conduits.

3. A manually movable pneumatic renovator comprising a platform having supporting wheels adjacent one end only, said wheels being located between the opposite ends of the platform and nearer one end than the other, a suction mouth carried by the other end of said platform and having its edges projecting below said platform and lying in a plane making an angle therewith, whereby said suction mouth may lie flat against the surface on which the rollers rest, while the platform lies at an angle thereto, and suction producing means mounted on said platform between the suction mouth and wheels, and communicating with said suction mouth.

4. A manually movable pneumatic renovator, comprising a platform supported between its ends only upon rollers about the axis of which the platform may be moved as a pivot, a casing at one end of the platform having a suction mouth, the surrounding edges of which lie in a plane below the lower surface of the platform whereby said mouth may be brought into direct contact with the surface being cleaned, a fan having communication with said casing and provided with an outlet for the dust laden air, and a motor for operating the fan, said motor and fan being mounted upon the platform between the rollers and mouth so that their weight normally serves to maintain the suction mouth in contact with the surface being cleaned.

5. A portable manually propelled renovator comprising an air conduit provided with a suction mouth in fixed relation therewith and a projecting spout adapted to receive a flexible hose for a cleaning tool, a valve controlling the passage of air through said conduit, a second valve controlling the passage of air through said spout, a motor, a fan casing having an intake opening with which said conduit is in communication, a discharge conduit leading from the periphery of said casing, and a fan within said casing connected with said motor.

6. A portable manually propelled pneumatic renovator, comprising an air conduit, a suction mouth in fixed relation therewith and adapted to be moved over the surface to be cleaned, and a projecting spout adapted

to receive a flexible hose, valve means for controlling the passage of air through said conduit and spout, a motor, a fan casing having an intake opening connected to and movable with said conduit, a discharge conduit leading from the periphery of said casing and a fan within said casing connected with the motor.

In witness whereof I have hereunto set my hand in the presence of two subscribing witnesses.
